United States Patent Office

Des. 229,749

Patented Jan. 1, 1974

229,749

VITAMIN TABLET OR SIMILAR ARTICLE

Ian C. Modelevsky, Pleasantville, Benjamin S. De Young, Sands Point, and Donald Nevins, East Elmhurst, N.Y., and Morley A. Stern, Mexico City, Mexico, assignors to Bristol-Myers Company, New York, N.Y.

Filed June 27, 1972, Ser. No. 266,821

Term of patent 14 years

Int. Cl. D1—01; D28—01

U.S. Cl. D16—3

FIG. 1 is a front elevational view of a vitamin tablet or similar article embodying our new design;

FIG. 2 is a top plan view thereof;

FIG. 3 is a right elevational view thereof;

FIG. 4 is a bottom plan view thereof;

FIG. 5 is a left elevational view thereof.

We claim:

The ornamental design for a vitamin tablet or similar article, as shown.
